[57] **CLAIM**

The ornamental design for a combined planter and holder for use within automotive vehicles, as shown and described.

DESCRIPTION

FIG. 1 is an exploded perspective view of a combined planter and holder for use within automotive vehicles showing my new design, the left side being a mirror image of the right and the rear and bottom being plain and unornamented;

FIG. 2 is a front view thereof; and

FIG. 3 is a top view thereof, the planter being omitted for ease of illustration.

FIG. 1

FIG. 2

FIG. 3
